[57] CLAIM

The ornamental design for an expansion joint sealing strip assembly for roadways and the like, as shown and described.

DESCRIPTION

FIG. 1 is a perspective view of an expansion joint sealing strip assembly for roadways and the like, showing my new design;

FIG. 2 is an end elevation view thereof, the sealing strip portion being an elastomeric member indicated by stippling having its ends interfitted in shaped recesses in channel members and having substantially triangular cross-section hollow center areas or voids which are filled with curable material which cures to a rigid state such as epoxy and the like indicated by heavier stippling;

FIG. 3 is a top plan view thereof; and

FIG. 4 is a bottom view thereof.
